UNITED STATES PATENT OFFICE.

JOHN A. WOLMER, OF INDIANAPOLIS, INDIANA.

STEAM-BOILER CONSTRUCTION.

1,106,066.

Specification of Letters Patent.

Patented Aug. 4, 1914.

Application filed December 24, 1913. Serial No. 808,598.

To all whom it may concern:

Be it known that I, JOHN A. WOLMER, a citizen of the United States, residing at Indianapolis, in the county of Marion and State of Indiana, have invented a new and useful Steam-Boiler Construction, of which the following is a specification, reference being had to the accompanying drawings, and to the letters and figures of reference 10 marked thereon.

This invention relates to boilers in which water may be heated, more particularly to steam generating boilers of the locomotive type, the invention having reference more 15 particularly to improved boiler construction with special reference to the crown sheet of fire-boxes.

An object of the invention is to provide an improved boiler construction relating 20 particularly to the crown sheets thereof to the end that the maximum degree of safety shall be attained when operating under a high steam pressure, and with a view to economy in construction and maintenance.

Another object of the invention is to provide an improved crown sheet construction 25 which shall permit the making of repairs in case of necessity without it being necessary in all cases to discard large sheets of 30 metal when only a relatively small portion may be defective or damaged.

A further object of the invention is to provide an improved sectional crown sheet 35 of such construction as to be adapted to be applied to boilers now in use having plain crown sheets provided either with crown bars or with radial stay bolts, and which improved crown sheet shall be adapted to present a relatively large amount of surface 40 to the fire-box heat so as to be highly efficient and economical in heating water or generating steam.

With the above mentioned and other objects in view, the invention consists in a 45 sectional crown sheet of novel construction in which the sections thereof are formed and arranged in a novel manner, the sections being so constructed and arranged as to permit of the removal and replacement of 50 any one of the sections.

The invention consists, further, in the novel parts and in the combinations and arrangements of parts as hereinafter particularly described and further defined in the 55 accompanying claims.

Referring to the drawings, Figure 1 is a central longitudinal section of a locomotive boiler fire-box constructed substantially in accordance with the invention; Fig. 2, a fragmentary horizontal section approximately on the line A A in Fig. 1; Fig. 3, a transverse section approximately on the line B B in Fig. 1; Fig. 4, an end view of one of the crown sheet sections; Fig. 5, a fragmentary section approximately on the line C C in Fig. 1; Fig. 6, a fragmentary section approximately on the line D D in Fig. 1; Fig. 7, a fragmentary section reproducing a portion of Fig. 3 on an enlarged scale; Fig. 8, a perspective view of 70 one of the crown sheet sections; Fig. 9, a perspective view of a bar preferably used between the crown sheet sections so as to practically form a part of the crown sheet structure; Fig. 10, a fragmentary section 75 similar to Fig. 7 excepting that various parts are slightly modified, and Fig. 11 is a transverse section of a square type of fire-box constructed in accordance with the invention.

Similar reference characters in the different figures of the drawings indicate corresponding elements or features of construction herein referred to.

For the purpose of clearly illustrating 85 and describing the invention well known features of boiler construction are briefly referred to and, as will be understood, may be variously modified as to details, a popular type of boiler construction comprising 90 a mud-ring 1, a boiler head 2, outer side sheets 3 and 4 and an arched top portion 5 connected to the side sheets integrally or otherwise a throat sheet 6 and a boiler shell 7 comprising the outer portions, the inner 95 portions comprising a fire-door sheet 8, side sheets 9 and 10, there being a door frame 11, and a flue-sheet 12 to which draft flues 13 are connected, stay bolts 14, 15, 15', 16, being appropriately used as is customary. 100 The sheet 8 has a flange 17 extending inward or away from the outer sheet 2, the flue sheet 12 having a flange 18 extending inward or toward the flange 17. A front flue-sheet 19, as will be understood, is connected to the shell opposite to the flue sheet 12.

It will be understood that in some cases a crown sheet is made continuous with the side sheets of the fire-box which necessitates 110

a large amount of troublesome work in making repairs in case of accidental injury to the crown sheet, in other cases although the crown sheet may be composed of a separate sheet of metal the whole sheet usually must be discarded in case of damage to only a small portion thereof. Also in some cases crown bars when employed prevent free circulation of water so that mud or scale rapidly accumulates upon the crown sheet to the detriment thereof; and when radial stays are secured directly to the crown sheet, as is a common practice, leaks frequently develop and in some cases the crown sheet is forced from the stay bolts. The evils of such forms of structure and the disadvantages thereof are obviated in the practical embodiment of the present invention, as will become apparent from the following detail description thereof.

The improved sectional crown sheet comprises a suitable number of sections composed of strips of metal sufficiently long to extend from the fire-door sheet 8 to the flue sheet 12 and of relatively narrow dimensions transversely, each section being suitably pressed or otherwise shaped so that the main portion 20 or 20' of the section is curved so as to be trough-like in normal position, the end portions 21 and 22 being suitably shaped so as to conform to the flanges 17 and 18 respectively upon which the end portions are supported, the end portions having rivet holes 23 and 24 therein respectively to receive rivets 25 and 26 whereby the end portions are secured to the flanges respectively. When the flanges 17 and 18 are arched it will be understood that the end portions 21 and 22 are arched. Each section has upturned flanges 27 and 28 formed thereon in which are rivet holes 29 and 30 respectively to receive securing rivets, the flanges of the adjacent sections being connected together so that they serve as crown bars or braces, and preferably separate bars 31, 31', are placed between the flanges of the adjacent sections to afford additional strength and also to be used in calking the seams in preventing leaks, each bar 31 corresponding in length to the length of the section and having downward offset bearing portions 32 and 33 on the under side of opposite end portions thereof adapted to rest upon the flanges 17 and 18 respectively, and on which a calking tool may be used. Each bar has a horizontal row of rivet holes 34 which receive rivets 35, 35', whereby the bar is secured between the two adjacent flanges of the adjacent sections, the bar extending upward above the flanges and the upper portion having a row of holes 36 therein that receive connecting bolts or pins 37, 37', whereby stay plates 38 are secured to the bars, the plates being connected also to angle plates 39 that are secured to the top portion

5, the plates being connected by means of bolts of pins 40 to the angle plates. The stay plates in some cases are preferable since they tend to prevent surging of the water on the crown sheet. In some cases, however; in 70 case radial stay bolts have been removed from the top portion 5, studs 41 may be inserted into the stay bolt holes, the studs having eyes 42 therein, and stay bars 43 having jaws 44 and 45 on opposite ends thereon may be connected respectively to the bars 31 and the eyes 42, or if desired two bars 46 and 47 75 obviously may be connected to the eyes as shown in Fig. 10. In some cases the upper portions or tops of the side sheets 9 and 10 are provided with flanges 48 and 49 respectively that extend into the water space or toward the outer portions 3 and 4 respectively, the bars 31, 31', being secured between the flanges and the flanges of adjacent 80 sections of the crown sheet.

In case the flat top or square fire-box is preferred the crown sheet is generally formed so that the ends of the sections correspond to a flat plane, instead of conforming to an arch as hereinbefore described. Such fire-box comprises side sheets 9' and 10' and the marginal crown sheet sections are provided with down-turned flanges 50 and 51 adapted to be secured to the upper portions 90 of the side sheets by means of rivets 52, 53, the upper end 54 of the fire-door sheet 8' being straight. In some cases the main portion of the crown sheet section may be shaped so as to form an arch 55 instead of a trough or inverted arch, as seen in Fig. 10. The outer portions 56 and 57 may be formed as usual as may also the top portion 58 which may be flat, the boiler head 59 being shaped correspondingly. The edges of the flanges 17 and 18 may be calked as usual and the calking tool may be used on the under side of the bars 31 so as to prevent leaks, and also the tool may be used against the ends of the bars.

In practical use the steam pressure is resisted not only by the sections of the crown sheet but by the bars 31 and also by the stays connected to the bars, so that the crown sheet is capable of withstanding excessive pressure. The sediment from the water gravitates and flows longitudinally from the section and may readily be washed therefrom. In case of accidental or unavoidable damage to one or more sections of the crown sheet, it is apparent that replacement may be made without sacrificing other sections.

Having thus described the invention, what is claimed as new is—

1. A boiler crown sheet section including 125 an oblong strip having straight flanges on its longer edge portions, the main portion of the strip between the flanges being curved transversely, the strip having end portions between the flanges that do not conform to 130

the curvature of the main portion, being adapted to conform to the tops of fire-door sheets and flue sheets.

2. In boiler construction, the combination 5 of a plurality of sections, each section being composed of an oblong strip having straight flanges on its longer edge portions, the strip being curved transversely between the flanges from a point distant from one end 10 to a point distant from the opposite end of the strip, the end portions of the strip beyond said curved portion having rivet-holes therein whereby to secure the two end portions respectively to a fire-door sheet and a 15 flue-sheet of a fire-box, and bars secured each between the flanges of two adjacent strips, the end portions of the bars being adapted to be supported respectively on the fire-door sheet and the flue-sheet.
- 20 3. In a boiler, the combination with two uprightly arranged side sheets, an uprightly arranged fire-door sheet, and an uprightly arranged flue-sheet, of a crown sheet comprising a plurality of separate sections connected together and collectively extending from one to the other of the side sheets, each 25 of the sections being secured at one end to the fire-door sheet and at its opposite end to the flue-sheet, a marginal one of the sections being secured to one of the side sheets, the opposite marginal one of the sections being secured to the remaining one of the side sheets.
- 30 4. In a boiler the combination of two side sheets having each a flange, two bars arranged upon the two flanges respectively,

two end sheets having each a flange connected to the side sheets, two crown sheet sections each having flanges, one flange of the two sections being arranged respectively 40 on the two bars, the sections being secured at opposite ends to the flanges of the two end sheets respectively, rivets securing the bars to the flanges adjacent thereto, and a plurality of crown sheet sections secured at 45 opposite ends to the flanges of the two end sheets respectively between the two crown sheet sections, each of the plurality of sections having two straight flanges thereon, the flanges of adjacent sections being 50 adjacently arranged, bars between the adjacent flanges and secured thereto, and a plurality of stays secured to each of said bars.

5. In boiler construction, a crown sheet comprising a plurality of separate sections, 55 each section being composed of an oblong strip having straight flanges on its longer edge portions, the strip being curved transversely between the flanges, a plurality of bars secured each between the flanges of two 60 adjacent strips and having offset bearing portions at opposite ends thereof, the bars extending beyond the flanges and having each a plurality of holes therein provided with staying devices, and stays removably 65 connected to said devices.

In testimony whereof, I affix my signature in presence of two witnesses.

JOHN A. WOLMER.
